(57) **CLAIM**

The ornamental design for a latch lock for a handle, as shown and described.

DESCRIPTION

FIG. 1 is a front perspective view of a latch lock for a handle in accordance with the present design;

FIG. 2 is a second front perspective view thereof, shown in an open configuration;

FIG. 3 is a front view of the latch lock for a handle of FIG. 1;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines represent unclaimed subject matter and form no part of the claimed design.
